UNITED STATES PATENT OFFICE.

WEBSTER C. ESTES, OF NEW YORK, N. Y.

DESIGN FOR A WOODEN SPRINKLING-BOTTLE STOPPER.

SPECIFICATION forming part of Design No. 32,085, dated January 9, 1900.

Application filed November 13, 1899. Serial No. 736,881. Term of patent 14 years.

To all whom it may concern.

Be it known that I, WEBSTER C. ESTES, a citizen of the United States, residing at New York, (Brooklyn,) in the county of Kings and State of New York, have invented and produced a new and original Design for a Wooden Sprinkling-Bottle Stopper, of which the following is a specification, reference being had to the accompanying drawing, in which a perspective view represents my new design.

The general configuration of the stopper is round; and the leading features of my design consist in the cylindrical configuration with a double-beaded edge and tapering contracting neck to the stopper and a double-beaded edge adjacent to the upper end.

The design of the stopper comprises the

cylindrical portion *a*, the double-beaded edge *b* of greater diameter than the cylindrical portion *a*, and the tapering contracting neck *c*, ²⁰ rising above the double-beaded edge *b* and terminating in the double bead *d* and the rounded end *e*.

What I claim is—

The design for a wooden sprinkling-bottle stopper, substantially as shown and described. ²⁵

Signed by me this 9th day of November, 1899.

WEBSTER C. ESTES.
